GRINDING WHEEL

Everard Stubbs, Springfield, Vt., assignor to
Norton Company, Worcester, Mass., a corpora-
tion of Massachusetts

Application December 31, 1932
Serial No. 649,671

4 Claims. (Cl. 51—206)

This invention relates to grinding wheels, and more particularly to a grinding wheel for grinding bodies of irregular contour, such as cams, splined shafts and the like.

5 In the art of forming work pieces of non-circular shapes, such as cams, by a grinding operation, the devices generally used involve a rotatable grinding wheel of a cylindrical shape and a work support which is arranged to reciprocate 10 the work to be ground back and forth in a path transverse to the grinding wheel axis, as the work rotates, in order that the grinding surface of the wheel may continuously engage the work throughout the entire surface contour. In such 15 a construction, this reciprocating motion is ordinarily effected by mounting the work on a swinging frame and automatically rocking the frame relative to the grinding wheel, which is fixedly mounted thereto, by means of a rotating pattern on the frame in contact with a 20 fixed follower. However, the use of this type of construction has not been very satisfactory and it has involved many difficulties owing to the complex movement utilized through which the 25 work must be cyclically moved during the grinding operation, the complicated form of machine construction required to effect such movement without variation in the grinding results, and the additional requirement that certain narrow 30 limits of diameter must be adhered to within which the grinding wheel may be used if satisfactory grinding results are to be obtained. Such a procedure has also resulted in a departure 35 from the true pattern to be ground and so is highly objectionable.

In accordance with the invention as set forth in my copending application Serial No. 612,232, filed May 19, 1932, I have there illustrated and described a grinding machine construction and 40 a method particularly adapted for forming bodies of various irregular and non-circular contours which does not involve any relative reciprocating motion between the grinding wheel and the work to present the work surface to be 45 ground continuously to the grinding surface of the wheel during the grinding operation. In that construction, it has been found feasible to employ a specially shaped grinding wheel, instead of the prior reciprocating arrangement 50 heretofore practiced, and this wheel is shaped as the conjugate of the work to be ground and is adapted to be rotated in angular synchronism with the work rotation during the grinding operation, in which case the wheel and work are

arranged to remain in a proper grinding phase relation at all times.

In the art of grinding cams or other irregularly shaped bodies involving a change in surface curvature, it is necessary that the grinding 60 wheel cut and wear away at substantially the same rate over its entire cutting surface to produce results true to pattern. However, it is found in practice that the grinding action of this shaped cutting wheel has not been uniform, and 65 that certain portions of the grinding face of the wheel, particularly those portions in contact with the sides of the cam leading from the heel portion to the toe, tend to wear away faster than does the remainder of the wheel, this being due 70 principally to the small, narrow arc of the wheel surface which is required to traverse rapidly across the more extensive sides of a cam and thereby is subjected to the greater wear. This excessive wear of the peripheral portions of the 75 grinding face necessitates frequent truing of the grinding wheel to bring it back to its correct form, thus involving a large loss of grinding time and wasting the substance of the wheel.

It is accordingly the primary object of my invention to overcome these difficulties experienced in conjugate grinding and to provide a grinding wheel which is not only of the desired shape and cutting condition, but is also of 85 non-uniform grinding characteristics throughout the grinding face and which will more efficiently grind work pieces of various irregular contours than will a wheel of uniform grinding properties throughout its periphery.

A further object is to provide a grinding wheel for forming bodies of irregular contour in which the grinding characteristics of the grinding surface vary in a peripheral direction, the portion of the wheel corresponding to the position of 95 greatest wear being adapted to compensate for such wearing tendencies and so retain the wheel wear substantially uniformly throughout the wheel periphery.

With these and other objects in view, as will 100 be apparent from the following disclosure, my invention resides in the subject matter described in the specification and set forth in the claims appended hereto.

In accordance with this invention, I propose 105 to provide a conjugate grinding wheel for use in grinding work of irregular contour, with a uniformly wearing grinding surface by making appropriate variations in the grinding characteristics in those portions of the wheel surface 110.

which are subject to excessive wear, the location of which is dependent upon the character of the work to be ground. That is, that portion of the wheel which is subjected to the heavier 5 grinding action and which will, therefore, be worn away more rapidly than other sections of the wheel is preferably made harder in its grinding characteristics or more resistant to wear than is another portion which is not called 10 upon to do such severe grinding. For example, if the work piece to be ground is a cam of the automotive type having a circular heel portion and sloping sides leading to the toe, then that portion of the wheel which is intended to grind 15 these sides and in which only a small arc of the grinding face will necessarily traverse across the more extensive surface of the cam slope is preferably made to have different grinding characteristics from that of the remainder of the 20 wheel, in order to make the wheel wear substantially uniform. Hence, for grinding a cam as thus described, this arc of the wheel substance should be made so as to be "harder acting" in its grinding characteristics. In practice, 25 I provide the wheel with a hard, wear-resisting grinding portion, such as an abrasive section or sector, located on the grinding face of the wheel at the points which are required to grind the slopes of the cam or in other positions of excessive 30 wear.

This hard wheel section may be made in various ways, such as by varying the size and kind of the abrasive grains used or by varying the amount of bond employed and, therefore, the 35 grade of hardness of the wheel, or by varying the structure of the wheel, i. e., the relative relationship of the abrasive, bond and pores. However, the essential condition in each case is to have that portion of the wheel which is called 40 upon to do the more severe work well adapted to stand up under the grinding operation and not wear away too rapidly, and so will not require the remainder of the grinding surface to be trued down to the extent of the worn surface. Moreover, it is desirable that this 45 particular sector or arc of the wheel be of such characteristics that it will grind the work surface contacting therewith with satisfactory results. Also, it will be understood that the sectors or sections of the wheel which are to be 50 made of different grinding characteristics from the remaining portions will have their length of arc determined by the work shape so that the harder acting sector will extend throughout the desired extent of work surface to be ground 55 thereby.

One embodiment of my invention is shown in the accompanying drawing, in which the figure is a diagrammatic view, in elevation, of one type 60 of grinding wheel showing particularly the relative location of the sections which vary in grinding characteristics as well as the relative relationship of the wheel and work for their various angular positions during the grinding operation. As there illustrated, the wheel comprises 65 an abrasive annulus or ring 10 having a curved outer grinding surface 11 and an inner cylindrical aperture 12 therein for mounting the wheel on a rotatable driving spindle. In the 70 preferred form, the grinding surface 11 may comprise an irregularly shaped contour which is the conjugate of the work to be ground. The grinding surface 11 is provided with several peripheral portions or sections 13 and 14 of vitrified 75 ceramic bonded abrasive grains having a

harder grade of hardness on the Norton scale and different grinding characteristics than the remaining portions 15 and 16 of the annulus integrally united therewith and composed of abrasive grains bonded with a vitrified ceramic bond and having a softer grade than the other portions. The harder bonded sections 13 and 14, which may be of the same or different grades of hardness and grinding characteristics, extend circumferentially around the grinding periphery and preferably in a radial direction inwardly to the spindle aperture 12, and they are separated by the portions 15 and 16 which are subjected to the lesser wearing tendencies. However, the extent and location of these harder bonded sections 13 and 14 are necessarily determined by the character and position of the work contour to be ground. 80 85 90

The wheel materials may be combined and shaped into a grinding wheel by suitable means and methods. For example, the vitrified grinding wheel may be made according to well-known methods employed in the art by molding in the desired form granular abrasive material, such as crystalline alumina or silicon carbide, mixed 100 with a suitable ceramic bonding medium, such as a suitable mixture of ball clay, slip clay and feldspar, as is known in the art, after which the wheel is baked at a temperature to "use or vitrify the bond. 105

As an illustration of one particular method of making a wheel having the grinding characteristics above described, which may be utilized for grinding a cam, I may first provide a moldable mixture for the hard portions by selecting 110 the proper quantity of crystalline alumina grains of a suitable size, such as one which will just pass through a screen having 50 meshes per linear inch, and a raw ceramic bonding material of standard formula, which are proportioned to 115 make the grade P on the Norton scale of hardness when the bond has been matured. This material is placed in a mold at the proper angular location with respect to the points of excessive wear, so as to form the sections or sectors 120 125 130 135 140 145 150 155 160 165 170 175 180 best for the particular operation to be performed. Various other types of bond may also be employed which are standard knowledge in the industry, depending upon the character of the material to be cut and the service and production desired. For example, one may utilize, in place of the vitrified ceramic wheel bonds, such bonding materials as shellac, rubber, sodium silicate or various resinoid materials, particularly those of the phenolic resinoid type. It is also within the scope of this invention to utilize different sizes of abrasive grains in the different sections 13, 14, 15 and 16 respectively, either coarse in the hard sectors 13 and 14 or fine in the other portions 15 and 16 or vice versa. The abrasive material may be used in a variety of sizes of grain, which is sometimes advantageous to obtain the required grinding characteristics, or the particles may be uniform in size. It is essential, however, that the bond of the harder acting sectors 13 and 14 be materially harder than that of the portions less subjected to excessive wear. It is furthermore within the scope of my invention to vary the grinding characteristics of the hard sectors 13 and 14 of the wheel by changing the grain size; that is, by employing grains of the finer sizes, so that the wheel portions containing this material will act harder in their grinding action, and so will not wear away as rapidly as would one embodying grains of a coarser size. Also, by using fine grains and properly proportioning the bond accordingly, the abrasive content of these sectors 13 and 14 may be materially increased to produce a harder grinding action. Likewise, the structure of these particular sectors may be made to a variety of abrasive packings so that they will be of a more dense nature and will, therefore, be harder acting and have different grinding characteristics. Various other manufacturing procedures well known in the industry may be employed to produce these hard and soft sections in the grinding wheel.

As illustrated, I have shown several dotted cam outlines, which serve to diagrammatically represent the actual portions of the cam contour which are successively placed in grinding contact with the particular sections of the grinding wheel there shown. It will be observed that this particular representation indicates six well-defined stages of the grinding operation. It will, therefore, be seen that if the rotation of the cam and the grinding wheel, on their respective axes, is assumed to be in a counter-clockwise direction and in angular synchronism with each other, as indicated in the drawing, then during the grinding operation, the grinding of the various portions of the cam contour there shown will take place as follows: The sloping side surface of the cam included between the angle "a" will be ground by the grinding wheel section 14 of harder acting characteristics; next, the cam arc included between the angle "b" will be operated on by the extensive wheel section 16 of lesser grinding properties; then, the sloping side surface included between the cam angle "c" will be subjected to the grinding action of the harder acting section 13; and lastly, to conclude the grinding operation, the portion included between the angle "d", which comprises the toe portion of the cam, will be ground by the remaining wheel section 15 of a softer grade of hardness than the preceding section.

In order to insure having the various wheel sections in exact angular relationship at all

times with the respective cam contour portions, as indicated in the drawing, I preferably so proportion and locate these wheel sections that the central angle formed by two radial planes and the included arc of the respective wheel contour will be substantially equal to the angle formed by two radii and the included arc of the cam of which the respective wheel section is the conjugate shape. It, of course, is to be understood that a high degree of mathematical accuracy is not required in fixing the length of arc of the sections, as the amount and location of such portions depend on the nature of the work to be ground and that, if desired, the portions of harder and softer grades may merge gradually into one another in order that there may be no sharp lines of division between the various sections of the wheel. It, of course, will be understood that this invention relates equally well to grinding wheels for grinding all kinds of bodies of irregular shape, such as splined shafts, which have peripheral surfaces of such shape that one portion of the wheel is required to have different grinding characteristics from another.

In accordance with this invention, I have thus provided a grinding wheel which has its various portions normally exposed to excessive wear in grinding work of irregular contour which is the conjugate of the grinding wheel surface and which is so made that the life of these portions will be increased and the contour of the grinding surface of the wheel will be maintained for a longer period of life than does the surface of the standard wheel. Such a wheel is intended, moreover, to give a more satisfactory grinding operation on those portions of the work surface which are not properly ground by the standard wheel employing a uniform mixture throughout the wheel periphery. For certain types of grinding operations, it is also within the scope of this invention to have a particular section in the wheel, such as the sector 15 which serves to grind the toe portion of a cam, made of a softer grade on the Norton scale and, therefore, a material of different grinding characteristics than the other portions 13, 14 and 16 respectively of the grinding face 11, to better accomplish a desired result. It will also be apparent that the grinding wheel may grind on either the periphery or the side faces, the grinding surface in either case being shaped to conform with the work surface as a conjugate thereof.

It is to be understood that the term "conjugate" as used in this specification and in the claims is associated with those curves which are so related as to be produced by the rotation of the connecting surfaces of the cutting wheel on the work about fixed axes with their angular velocities equal or in a simple ratio where these surfaces are in part irregular in shape and their peripheries are of unequal extent. If the work and wheel were rotated in opposite directions and their circumferences were the same in length and their angular velocities were the same, the two surfaces would have a pure rolling contact; but with the dissimilarity of length of the two peripheries, a slipping or cutting action between the wheel and work serves to grind the latter to size. If the wheel and the work are rotated in the same direction, the cutting conditions are the same as in a normal cylindrical grinding operation. They may be rotated in opposite directions if desired. It is essential, however, that the work and the grinding wheel rotate

in fixed angular synchronism and that the wheel be so shaped that for each revolution thereof, it will reproduce a conjugate shape on the work. The work and the wheel are said to be in "angular synchronism" when their angular velocities are in simple ratio of one to one, two to one, three to one, etc. In other words, the wheel and work are always rotated to a proportionate angular displacement.

10 It is to be understood that the wheel covered by the present invention may be applied to forming eccentrically revolved cylindrical surfaces, such as crankpins, as well as non-circular peripheral surfaces, the cross-section or contour 15 of which does not form geometric circles, such as cams, and to the forming of irregular surface contours on the side faces of rotary bodies; hence the expression "work of non-circular contour" and similar wordings found in the 20 claims are to be interpreted as covering such shapes. The invention applies equally to grinding holes of an irregular shape by forming the grinding wheel so that when it rotates in synchronism with the work blank, it will produce a 25 conjugate surface in the inner peripheral surface of the work. Various other applications of this invention are clearly within the scope of the appended claims.

Having thus described my invention, what I 30 claim as new and desire to secure by Letters Patent is:

1. A grinding wheel comprising a body of bonded abrasive grains having a preshaped grinding surface of non-circular contour which 35 is the conjugate of the work face to be finished, said wheel having a grinding surface portion of definite grinding characteristics adapted to grind a definite portion of the work, and a further abrasive portion of different grinding char- 40

acteristic which is adapted for grinding another portion of the work as the work and the wheel are revolved in angular synchronism.

2. A grinding wheel comprising a body of bonded abrasive grains, the grinding periphery of which is shaped as the conjugate of the contour of the finished work piece, said wheel having a section made of abrasive grains and bond adapted for grinding a definite portion of the work surface, and a further section of harder grinding characteristics which is adapted to grind another section of the work surface as the grinding wheel and the work are rotated in angular synchronism. 80

3. A grinding wheel comprising a body of bonded abrasive grains having a peripheral grinding surface adapted to grind the heel portion of a cam, the contour of said cam being shaped as the conjugate of the grinding wheel, and a plurality of sections of harder grinding characteristics thereon which are adapted to grind the sides of the cam leading from said heel portion and are so located as to present a sufficient extent of harder grinding characteristics which will contact with substantially the entire extent of said sides of the cam. 90

4. A grinding wheel of the type covered by claim 1 in which the grinding body has a plurality of spaced sections of a definite grade adapted to contact with the opposed portions of the work surface, said parts being separated by sections of abrasive material which are of harder grinding characteristics and which subtend such arcs of wheel surface as to contact with those parts of the work surface which are to be 105 ground thereby. 110
